[57] CLAIM

The ornamental design for a tooth brush holder, as shown and described.

DESCRIPTION

FIG. 1 is a top plan view of a tooth brush holder showing my new design;

FIG. 2 is a front elevational view thereof;

FIG. 3 is a left side elevation view thereof; and

FIG. 4 is a right side elevational view thereof.

The rear elevational view of the tooth brush holder is flat and unornamental.
